(57) **CLAIM**

The ornamental design for a chair, as shown and described.

DESCRIPTION

FIG. 1 is a perspective view of a chair embodying our new design.

FIG. 2 is a front elevational view of the design.

FIG. 3 is a side elevational view of the design, the opposite side being a mirror image thereof (with or without the handle shown in phantom in FIG. 1).

FIG. 4 is a rear elevational view of the design; and,

FIG. 5 is a top plan view of the design.

The broken line structure of the figures is for environmental purposes and forms no part of the claimed design.
